(57) **CLAIM**

The ornamental design for a storage and dispensing carafe, as shown and described.

DESCRIPTION

FIG. 1 is front, perspective view of a storage and dispensing carafe manifesting the invention.

FIG. 2 is a front elevation of the storage and dispensing carafe illustrated in FIG. 1.

FIG. 3 is a rear elevation of the storage and dispensing carafe illustrated in FIGS. 1 and 2.

FIG. 4 is a left side (with reference to the carafe positioned as shown in FIG. 2) elevation of the storage and dispensing carafe illustrated in FIGS. 1 through 3.

FIG. 5 is a right side (with reference to the carafe positioned as shown in FIG. 2) elevation of the storage and dispensing carafe illustrated in FIGS. 1 through 4.

FIG. 6 is a top view of the storage and dispensing carafe illustrated in FIGS. 1 through 5; and,

FIG. 7 is a bottom view of the storage and dispensing carafe illustrated in FIGS. 1 through 6.
